DRY SHAVER

George R. Ericson, Kirkwood, Mo., and Ralph T. Bassett, Washington, D. C.

Application January 27, 1938, Serial No. 187,292

10 Claims. (Cl. 30—43)

This invention contemplates an improvement in a shaving structure capable of manual or power actuation, the manual actuation being by virtue of a removable cutting blade conventionally utilized in connection with wetting or softening agents such as creams, lathers and the like, and the power actuation being of the so-called dry shaver type and embodying the use of a shearing element cooperating with the cutting blade.

One of the objects of this invention is to provide in conjunction with the conventional razor cutting blade, a cooperating movable shearing face, the latter embodying a multiplicity of minute cutting faces.

A further object is to provide the movable shearing element with small pockets, a portion of the wall of each pocket defining the shearing face.

More specifically this invention embodies the use of a shearing element in which there is provided a number of small shearing faces each of which is formed by a portion of a wall of a pocket which is of such diameter that it will not, during its travel in cooperation with a shearing face, envelope or carry a portion of the surface being shaved, thus eliminating the possibility of injury to this surface.

The invention further contemplates the provision of travelling means for the shearing element and/or the cutting blade whereby the required speed and movement between the cooperating parts is provided, the movement being rotary, oscillatory or otherwise as may be desired or found practical in an assembly of this character.

A further object is the provision and arrangement of the parts whereby relative adjustment between the shearing faces may be provided to obtain maximum efficiency under working conditions.

Further objects will more clearly hereinafter appear by reference to the accompanying drawings forming part of this specification and wherein like numerals of reference designate corresponding parts throughout the several views, in which

Fig. 1 is a fragmentary side elevation partly in section of one modification of the invention,

Fig. 2 is a front elevation of Fig. 1,

Fig. 3 is a vertical section of a modified form of drive mechanism for the structure shown in Fig. 1,

Fig. 4 is a longitudinal section through the structure of Fig. 3,

Fig. 5 is an enlarged view of the shearing block used in the modification of Figs. 1 to 4,

Fig. 5' shows a modified form of two-way shearing mechanism,

Fig. 6 is a side elevation partly in section of a modified form utilizing a flat laminated shearing face,

Fig. 7 is a top plan view of Fig. 6,

Fig. 8 is a front elevation of another modified form,

Fig. 9 is a side elevation partly in section of the disclosure of Fig. 8,

Fig. 10 is a detail of the shearing block utilized in Figs. 6 and 7,

Fig. 11 is a side elevation partly in section of another modification utilizing an oscillating type of shear block,

Fig. 12 is a front view partly in section of the structure of Fig. 11,

Fig. 13 is an enlarged view of the oscillatory shear block of Figs. 11 and 12,

Fig. 14 is an enlarged fragmentary detail view of a portion of Fig. 13 showing the shearing blades and separator blades disassembled, and

Fig. 15 is a vertical sectional view of the modification of Fig. 11 and with a different drive mechanism.

Referring now to Fig. 1, a motor casing is indicated at 1 and may be of any size or shape to accommodate a suitable motor or power element of proper design. This motor casing is shown partly in section to expose a drive shaft extension 2 actuated from the motor 3, the latter being illustrated in dotted lines. One end of the casing 1 is formed with an extension 4 slotted at 5 to provide a pocket in which is positioned the bearing 6 which accommodates the shaft 2. A shoulder 4' supports the lower end of the bearing 6 and this shoulder also supports the lower end of the tubular casing 7 which encloses the bearing and also the upper end of the drive shaft 2. The upper end of the casing is formed with a socket 8 in which the upper extremity of the shaft 2 is mounted. Between the upper end wall of the casing 7 and the bearing 6, a cam 9 is positioned, the cam being mounted as by splining on the shaft and driven thereby. The casing 7 is formed with a tubular horizontally arranged extension formed of upper and lower curved walls 10 and 11 providing a cylindrical elongated open front casing which accommodates the fixed and movable shearing elements. The cam face 14 of the rotary cam 9 engages the rounded extremity 15 of the shank 16 which projects from the shearing cylinder 17 enclosed between the

walls 10 and 11. This shearing cylinder may be, as illustrated, of several forms and is suitably mounted in the present instance for oscillatory movement on the shaft 18 the ends of which are seated in bearings in the end walls. The cylindrical shearing element 17 is provided for a portion of its surface with a multiplicity of minute pockets 19 a portion of the wall of each of which provide shearing faces for cooperation with cutting blades 20, 20'. Each of these blades 20 10 and 20' are removably clamped to the inclined outer faces 21 of the wall extremities 10 and 11, these inclined faces being designed at such an angle as to bring about a proper relationship between the blades 20-20' and the shearing faces formed in the shearing cylinder 17 whereby the desired cutting action will be provided between these parts. Hinged spring plates 22-22' hold the blades 20-20' under proper tension and against the shearing cylinder and these hinged spring plates 22-22' are secured by any suitable means such as the pivoted spring plates 23 in clamping position.

It will be noted from this structure that the bearing 6, casing 7 and related parts may be removed from the motor casing 4 by release of the thumb-screw 24 which is provided on the threaded stud 24'. The stud 24' extends through the casing 7 and into the bearing 6 and retains these parts against relative movement. The stud is likewise shown as removable. The removal of this upper assembly permits access to the cam and bearing by removal of a section of the casing as is obvious. The specific form of casing is capable of numerous changes in structure to facilitate substitution of parts and types of mechanisms and reduce the cost of manufacture.

In Figs. 3 and 4 a modified form of drive is shown. The casing structure is similar to Figs. 1 and 2 except that a horizontal wall 25 is provided with a socket 25' to position and support the bearing 26 upon which is mounted the gear 27 which meshes with the gear 28 on the horizontal shaft 29 supported by the vertical walls 30, 30'. The wall 30 is formed with a horizontal opening which extends entirely through the same and the wall 30' is formed with an opening merely for the end of the horizontal shaft 29. By this means the shaft may be inserted through the wall 30 into the wall 30'. On the shaft 29, which is driven by the gears 27 and 28 is the gear 31 which meshes with the gear 32 supported in journals 33, 33'. The gear 32 meshes with an intermediate row of teeth 34 formed in the shear cylinder 35. These teeth may have the shearing faces as the balance of the teeth formed by the pockets as in Figs. 1 and 2. In Figure 5 the structure of the shear drum is illustrated and it will be noted that the shear faces 36 of the pockets are arranged at a slight angle with respect to the axis of the shear cylinder to facilitate the escape of the shear face across the blade. In Fig. 5' a modification is shown of a shear cylinder for use in such assemblies as shown at Figs. 1 and 2 and in this illustration it will be noted that shear block laminations have hook extensions 17' which are alternately arranged and overlap at their extremities. The forward edge 17'' of each hook constitutes the shearing face and each shearing face is spaced by the blade 70 supporting intermediate surfaces.

In Figs. 6 and 7 the same casing is provided with the drive shaft 2 formed with an eccentric pin 40. This pin seats in a socket formed in a flat shear block 41. The shear block 41 may be 75

formed of a single structure or as a laminated structure, with each lamination the width of the kerf or notch and the laminations staggered so that the pockets are defined and spaced. This pocket arrangement is shown more clearly in Fig. 7. In this form of the invention the removable cutting blades 43 and 44 are held by hinged clamps 45 and 46, these latter being held in clamped position by the clips 47. If desired only one cutting blade may be utilized and in this case the shear block will be of reduced width, determined by the cam movement and the size of the minute shear faces.

In Figs. 8 and 9 a structure is provided in which the shell portion connecting the shear cylinder 50 with the casing is of angular form. In this type power is transmitted through the shaft 2 from the motor through beveled gear 51 to beveled gear 52, the latter being mounted on the shaft 53 fixed in bearing block 54. The upper end of the shaft 53 is provided with the disk 55' upon which is formed the eccentric pin 56 which engages in a pocket 57 in the cylindrical shear member 50. In this form of the invention the blades 58 and 58' are clamped in position by the hinged clamps 59 and 60 secured to the cross bars 61 and 62. These cross bars 61 and 62 are fixed at the ends of the hinged arms 63 and 64 pivoted on the shaft 65. The shaft 65 also mounts the shear roller or cylinder 50. A spring 66 is positioned between the arms 63 and 64 to secure the necessary tension between these arms for the proper engagement of the blades 58 and 58' with the shear cylinder 50. Cams 67 and 68 are mounted for rotation on the projections 70 and 71 and the rotation of these cams 67 and 68 shift the arms 63 and 64 forwardly against the tension of the spring 66 whereby the spacing of the blade on the shear cylinder is determined. The spring upon further shifting of the cam will separate the blades inasmuch as the arms under the spring tension will normally swing outwardly for engagement against the cams 67 and 68.

In Fig. 11 a two part casing 80 is provided and in this casing the vibrating motor 81 actuates the control arm 82 to rock the shear cylinder 83 on its pivots 84. The shear cylinder 83 is formed as best shown in Figs. 13 and 14, of a multiplicity of disks 83, each alternate disk 83 embodying a shear face and being spaced by a thinner disk structure 83'. The spacer disk may be of minimum thickness, i. e., ten thousandths of an inch and just sufficient to properly space and define the pockets forming the shear faces. A removable blade holder 90 is fixed to the cap 91 closing the casing 80 by means of bolt 92 and a hinged plate 93 clamps the blade 94 in position on the beveled face 95 and in working contact with the minute shear faces formed in the cylinder. The blade holder may be shifted by releasing the bolt 92 and in this manner the position of the blade with reference to the shear face can be quickly and easily adjusted. This adjustment is contemplated inasmuch as it may be found desirable to utilize thin cutting blades of different width. The blade utilized is preferably of the type conventionally used on safety razors and may have either one or two cutting edges as desired. In the illustrations only one cutting edge is shown, however, a double edged blade may be readily substituted and utilized. The present modification is particularly adaptable for use either as a dry or wet shaver and when used in either manner the desirable adjustments, if necessary, may be

made by the movement of the blade holder by means of the bolt 92.

Where the shear block, in any of the forms shown and described, includes a multiplicity of laminations, they will be assembled in proper relationship and retained by such means as the longitudinally extending pin 96. This means of retaining the laminations in their proper association can be varied as necessity may require. It will be further noted that in the various assemblies guards may be provided at the ends of the shear block. Also a guard bar 100, illustrated in the modification of Fig. 11, may be adapted to facilitate the proper positioning of a cutting element with relation to the surface being shaved.

As heretofore stated Fig. 15 is a vertical sectional view of the modification of Fig. 11 with a different drive mechanism. In this figure the shearing mechanism has been identified, where possible, by reference characters corresponding to those in Figure 11 primed. Thus, in Fig. 15 there is illustrated the blade holder 90' fixed to the cap 91' closing the casing 80 by means of the bolt 92'. A hinged plate 93' clamps the blade 94' in position on the beveled face of the blade holder and in working contact with the minute shear faces formed in the cylinder 83'. The formation of the shear member is preferably as indicated in Figs. 13 and 14. To facilitate shaving a guard bar 100' is illustrated. The shear head 83' is oscillated with respect to the blade 94' by means of eccentric pin 101 on the rotary shaft 2, the eccentric pin 101 engages in a recess 103 formed in the bottom portion of the shear block assembly.

In each of the modifications there is provided a thin cutting blade which may be of the standard safety razor type, with single or double cutting edge and capable in itself of a shaving operation. In addition to this thin cutting blade there is a shearing member which cooperates with this cutting blade and which embodies a multiplicity of blunt durable shearing edges. This shearing member is adapted for cooperation with the cutting blade and in the various modifications is applied with power whereby the relative movement between the blade and the shearing member is obtained. The multiplicity of blunt and durable shearing edges are formed in the shearing member, by providing in same a multiplicity of pockets, a portion of the wall of each pocket defining the shearing edge. Further, the shearing edges are spaced as shown in the different modifications and this spacing may be obtained by staggering the pockets or by providing between the pockets a thin spacing element. The wall portion of the shearing member spacing the shearing faces supports the cutting blade throughout its length and retains it in proper relation to the shearing edges.

In instances where power is not available to utilize the present structure as a dry shaver it can be utilized in the same manner as the standard safety razor. This is particularly true when only one cutting blade is embodied in the assembly. Relative adjustment between the cutting blade and the shearing member can be made by any suitable means as by bolt 92 in the last modification described and this adjustment may be utilized to facilitate the conventional shaving operation where power is not present.

When essential a rubber gasket 105 can be placed between the head structure and the drive mechanism, this gasket being preferably of light

rubber and suitably bonded to the frame. A reinforced opening is formed at a proper point in the gasket to accommodate the drive arm from the motor. This gasket may be essential in some instances and in other instances the motor casing itself can be so constructed and arranged with respect to the head that leakage between these parts is not present.

We claim:

1. A dry shaver comprising a quickly detachable, flexible blade and a shearing member cooperating therewith, said shearing member having a series of whisker receiving recesses, shearing edges, and blade supporting members extending along the edge of the blade, said blade having an edge in substantially line contact with said supporting members, and means for holding the blade in resilient sliding contact with said members.
2. A motor driven razor comprising a blade, a shearing member having a multiplicity of supports longitudinally spaced along the edge of said blade and making a substantially rectilinear series of contacts therewith, shearing edges formed between said supports and forming a continuation of a straight line of contact between said blade and said supports, said shearing member being substantially out of contact with said blade except for the edge thereof, and means for maintaining a resilient contact between said edge of said blade and said supports.
3. A motor driven razor comprising a frame having a blade supporting portion, a blade supported by said portion, a spring device for detachably holding said blade in position, a shear member having a multiplicity of supports in resilient contact with the edge of said blade and substantially free of contact from any other portion thereof, shearing edges mounted in a line of contact between said blade and said supports, and means for rapidly oscillating said shearing member.
4. In a razor structure, a blade carrier, a blade in said carrier, a shear member movable with relation to the blade and said shear member including a multiplicity of longitudinally arranged relatively small pockets each formed to include a shear face defined by spaced walls, said walls forming blade supporting members, and the shear face of each pocket coacting with said blade, and said blade carrier being adjustable to shift said blade relative to and in contact with said shear member.
5. In a razor structure, an adjustable blade carrier, a blade in said carrier, an oscillating shear member movable with relation to said blade, said shear member including a multiplicity of relatively small longitudinally arranged spaced pockets, each pocket having a shear face coacting with said blade, said shear member being provided with blade supporting walls, means for maintaining resilient sliding contact between said blade and said walls, and means for adjusting said blade carrier to vary the position of said blade on said shear member.
6. In a razor structure, a housing, a quickly detachable relatively thin resilient sheet metal blade having a continuous cutting edge, a rapidly shiftable shear member movable with relation to said blade, said shear member being formed with a multiplicity of relatively small spaced pockets, one wall of each of which includes a shearing edge, said shearing edges having intermittent resilient line contact with the cutting edge of said blade, relatively short spaced

wall portions further defining said pockets and normally engaging and supporting said resilient blade during movement of said shear member to and from engagement with said cutting edges, and means in said housing for shifting said shear member.

7. In a dry shaver, a flexible cutting blade having a straight cutting edge and a rapidly oscillating shearing element formed with a multiplicity of spaced minute shearing faces each of which is substantially parallel to the axis of said shear member for cooperating with the edge of said cutting blade, the shearing faces at the time of cooperation with the blade being associated with a relatively small recess whereby injury to the body being shaved is avoided, said shearing element having a multiplicity of blade supporting portions adjacent said shearing faces, and said blade being held in resilient sliding contact with said supporting surfaces by its own flexibility.

8. In a dry shaver comprising a blade having a thin flexible straight razor edge, a shear member having a series of supporting portions spaced along said razor edge at intervals, shear edges

between said portion adapted to make line contact with said blade edge, said supporting portions contacting substantially only with the edge of said blade, and means for resiliently maintaining said contact.

9. In a dry shaver, a thin flexible blade having a straight cutting edge, a shearing block adapted to cooperate with said blade and including a multiplicity of shearing edges arranged for simultaneous line contact with said blade edge, each shearing edge being provided with hair receiving pockets the side walls of which are relatively thin and form blade supporting elements as said shearing edges approach said blade cutting edge, and portions extending from said shear faces and forming blade supporting elements after said shearing edges pass over said blade cutting edge.

10. The substance of claim 9 characterized in that means are provided to regulate the travel between the blade edge and shear face during shearing operation.

GEORGE R. ERICSON.
RALPH T. BASSETT.
